CLAIM

The ornamental design for a fan with a solar panel, as shown and described.

DESCRIPTION

FIG. 1 is a right-angled perspective view of the fan with a solar panel in a tilted position of use;

FIG. 2 is another right-angled perspective view thereof, with the solar panel in a recessed position of use;

FIG. 3 is a left-angled perspective view of the fan with a solar panel of FIG. 1; and;

FIG. 4 is a straight on perspective view of the fan with a solar panel of FIG. 2.

The broken lines in the drawings showing the flashing beneath the fan with a solar panel depict environmental subject matter only and form no part of the claimed design.

The broken lines in the drawings that show the hinged bracket for the solar panel depict parts of the fan with a solar panel that form no part of the claimed design.
